MINER P. WETMORE, OF NORWICH, CONNECTICUT, ASSIGNOR TO THE AMERICAN THERMOS BOTTLE COMPANY, OF NORWICH, CONNECTICUT, A CORPORATION OF OHIO

APPARATUS FOR USE IN SILVERING VACUUM BOTTLES

Application filed June 8, 1927. Serial No. 197,411.

My invention relates to the manufacture of double-walled vacuum bottles in which two glass cylinders (known as the filler) are separated by an evacuated annular space or chamber. It is customary to silver the walls of the vacuum chamber to improve the heat-retaining properties of the bottle. The silvering is usually done by means of a silver solution from which metallic silver is precipitated 5 on the walls of the vacuum chamber as a thin and substantially uniform coating.

The object of the present invention is to provide improved methods and means for introducing a predetermined quantity of a 15 silvering solution into the vacuum chamber in a rapid and efficient manner. For this purpose I mount one or more fillers on a support having controllable connections with a vacuum pump and with a receptacle containing the silver solution. After the filler is put 20 on its support, the operator need only depress a pedal (or move an equivalent member) whereupon the following operations take place automatically: The bottle is first connected with the vacuum pump to exhaust the 25 annular space between the two cylinders, and then the evacuated chamber is connected with the receptacle containing the silver solution, of which a measured quantity is instantly 30 drawn into the vacuum chamber. Just before the silver solution is drawn into the bottle, it is necessary to put into it a small amount of acid to effect the subsequent precipitation of the silver. A fixed amount of 35 acid flows into the silver solution from a cup, which is automatically tilted just before the evacuated bottle is opened to the solution receptacle. The filled bottle is removed for 40 further treatment and an empty one is put in its place. The filling operation requires only a few seconds. The mechanism for accomplishing this result is comparatively simple. One operator can easily take care of two 45 bottles on the machine at the same time; while

one bottle is being evacuated, the other is being filled.

The advantages of my invention will be fully understood from a description of the machine illustrated in the accompanying 50 drawings, in which—

Fig. 1 is a side elevation of a filling machine constructed in accordance with my invention;

Fig. 2 is a fragmentary view on a larger 55 scale showing the acid cup in tipped position;

Fig. 3 is an enlarged detail view in perspective, showing one of the cam mechanisms for operating the valves that control the evacuating and filling operations for the bottles 60 on one of the tubular supports;

Fig. 4 is a fragmentary view, partly in section, showing certain parts of the cup-tilting connections;

Fig. 5 is a plan view of the machine; 65

Fig. 6 is a view similar to Fig. 3, showing the second cam mechanism, which controls the evacuating and filling operations for the bottles on the other support;

Fig. 7 is an enlarged detail view in section 70 to show how the valve-actuating cams are clutched to the driving shaft through one revolution, and

Fig. 8 is a face view of the clutch disk associated with the controlling cams. 75

On a suitable table 1 is mounted a system of tubes or pipes, which in this instance consists of four flexible tubes 2, 3, 4 and 5, a pair of T-shaped connectors 6 and 7, and a central connection 8. The flexible or collapsible 80 tubes are preferably made of reinforced rubber, and the connecting pieces may be glass tubes fitting air-tight into the ends of the rubber tubes. Suitable brackets hold the connecting pieces firmly in position. This system of tubing terminates at its ends in a pair of L-shaped tubes 9 and 10, usually of 85 glass, which dip into cups 11 and 12, respectively. These cups, which contain the silver solution, are suitably supported at the 90

ends of the table, as by means of brackets 13 secured to the front table legs 14. A pair of brackets 15 extend rearwardly of the table for supporting storage bottles 16, which supply the silver solution to receptacles 11 and 12. 5 For this purpose there are pipe connections 17 between bottles 16 and cups 11 and 12, as best shown in Figs. 1 and 2. Each of the supply bottles 16 is provided with an air-tube 18, which extends to a certain distance above the 10 bottom of the bottle. This is to regulate the quantity of solution flowing into cups 11 and 12 for each filling operation. By adjusting the height of tube 18, the quantity of silver 15 solution flowing into the cups can be regulated to the required measure.

The T-shaped connecting pieces 6 and 7 are each formed with a tubular arm 19, which extends upwardly and is inclined rearwardly 20 at a convenient angle, as shown in Figs. 1 and 5. The tubular arm 19 is adapted to receive the tubular extension 20 of a double-walled glass 25 filler or bottle 21. The receiving end of arm 19 is preferably made of rubber or like material in order to effect an airtight fit with the filler, which is held in proper position by resting on a bracket 22 mounted on the table top. Each bottle is thus held by the tubular arm 19 at one end and by the bracket 22 30 at the other end, so that the parts 19 and 22 may be referred to as a bottle support. The central pipe or tube 8, which connects the 35 flexible tubes 3 and 4, is connected with a vacuum pump (not shown). The dotted line 23 in Fig. 5 represents diagrammatically a connection leading from pipe 8 through the table top to a vacuum pump V located at a suitable place. This will be understood without additional illustration especially since I 40 lay no claim to any particular construction of vacuum pump.

On the table top are mounted two pipes or tubes 24 and 25, which connect with a T-shaped piece 26. A tube 27 connects member 26 with an acid bottle or holder 28 on the table. An air tube 29 in bottle 28 regulates the supply of acid in the same manner as described in connection with the silver solution bottles 16. The pipes 24 and 25 connect 45 with small cups 30 and 31, respectively, which are tiltably mounted on tubular extensions or bearings 32, as best shown in Fig. 2. When the cups 30 and 31 are in normal upright position, they are open to the acid bottle 28 for 50 receiving a predetermined quantity of acid. For this purpose, each cup is formed at the bottom with an opening 33 adapted to communicate with pipe connections 24 and 25. The acid cups are so arranged that, when 55 tilted, the contents are discharged into the silver solution contained in the adjacent receptacle 11 or 12. This is clearly seen in Fig. 2. The mechanism for tilting the acid cups 60 at the proper moment will be described later 65 on.

Along the front edge of the table are pivoted four arms, designated by 34, 35, 36 and 37. These arms are mounted at the front end on brackets 38 by means of pins 39. It will be observed from Fig. 5 that the arms 34-37 are arranged transversely over the flexible tubes 2-5, respectively. When each arm is depressed, it pinches the tube beneath to close the same, very much like a pinch-cock. To facilitate this pinching action of arms 34-37, I provide a block 40 on the table beneath each tube 2-5 in line with the associated arm. In the broad view of my invention, the arms 34-37 may be regarded as a suitable form of valve for controlling the evacuating and 70 filling operations to be described. The valve arms 34-37 are connected at their rear ends to levers 41, 42, 43 and 44, respectively, by means of vertical links 45. The levers 41-44 are pivoted at 46 to suitable brackets 47 beneath the table. 75

It is clear from the foregoing that, when the front end of a lever 41-44 is rocked downwardly, the connected arm 34-37 is pulled down to close the flexible tube 2-5. 80 When the valve arms 35 and 36 are pulled down by levers 42 and 43, the bottle supports 6 and 7 are cut off from the vacuum pump. When the valve arms 34 and 37 are pulled down, the bottle supports are disconnected from the solution cups 11 and 12. 85 As will presently be explained, the levers 41-44 are so timed that when the valve arm or pinch-cock 35 is opened to connect a bottle on support 6 with the vacuum pump, the valve arm 34 is down to close off the bottle from the solution cup 11. Conversely, when the arm 35 is down to cut off the vacuum, the arm 34 is up to connect the bottle with the solution 90 cup 11. The same operative relation holds 95 true for valve arms 36 and 37. The two valve arms 34 and 35 are so timed relatively to arms 36 and 37 that, when the arm 35 is down, the arm 36 is up, and when the arm 34 is up, the arm 37 is down. As a result of this timing, 100 when the bottle on support 6 is open to the vacuum pump, the bottle on support 7 is open to the solution cup 12, and vice versa. 105

I now come to the mechanism for controlling the valve members 34-37 in properly timed relation to effect the sequence of operations described in the preceding paragraph. At the back of the table runs a power shaft 48 mounted in bearings 49. As a source of power for shaft 48 I have indicated an electric motor 50 geared to the power shaft through a drive chain 51 and reducing gears 52. Any suitable means may be used to drive the shaft 48 continuously at the correct speed. On power shaft 48 are mounted two pairs of cams 53-54 and 55-56. Each pair of cams may be cast as a single member. A clutch disk 57 is fixed on shaft 48 adjacent each pair of cams, which are normally loose on the power shaft. Cam 53 is formed with a high 110 115 120 125 130

track 53^a and a low track 53^b. The adjacent cam 54 has a high track 54^a and a low track 54^b. As best shown in the enlarged view of Fig. 3, the high and low tracks of cams 53 and 54 are arranged 180 degrees apart, and each track occupies about half the circumference. The rear end of lever 41 carries a roller 58 arranged to engage cam 53. A roller 59 mounted on the rear end of lever 42 runs on cam 54. These rollers are continuously held in firm contact with their respective cam tracks by coil springs 60 attached to the levers near their front ends.

What has been said about cams 53 and 54 of Fig. 3 applies fully to cams 55 and 56 of Fig. 6, the only difference being that the corresponding operative surfaces of the two pairs of cams are relatively displaced 180 degrees. This is clear by simply comparing Figs. 3 and 6. I need therefore only mention that 55^a and 55^b indicate the high and low tracks of cam 55, and 56^a and 56^b designate the high and low tracks of cam 56. The rear end of lever 43 carries a roller 61 held constantly in engagement with cam 55, and a roller 62 at the rear end of lever 44 rides over cam 56.

Each pair of cams 53-54 and 55-56 is connected to and disconnected from the associated clutch disk 57 by means of the following mechanism, which is duplicated for each pair of cams, so that a description of one is sufficient for both. From one face of each pair of cams projects a frame 63 forming a radial recess 64, in which is mounted a block 65. The frame 63 may conveniently be cast integral with the cams. The block 65 is mounted to slide axially in recess 64 and carries a pin 66 arranged to extend axially through the adjacent cam, as best shown in Fig. 7. Each pair of cams 53-54 and 55-56 is provided with a cylindrical chamber 67 in which is housed a coil spring 68. The pin 66, which always moves with the block 65, terminates in a head 69 having a locking projection 70. The normal tendency of spring 68 is to push the projection 70 into a hole 71 in clutch disk 57. As seen in Fig. 8, the holes 71 are arranged circularly as close together as possible without weakening the disk. The slideable block 65 is formed on top with a beveled face 72 arranged to be engaged by a correspondingly beveled head 73 on a lever 74 pivoted at 75 on a bracket 76 below the table. For the sake of distinction I have used the reference numeral 74' in Fig. 6 to indicate the lever which carries the cam-head 73.

Below the table are two pedals 77 and 78, which are connected by links 79 to the levers 74 and 74'. A coil spring 80 normally holds the cam head 73 downwardly in engagement with the cam face 72 of the slideable block 65. This means that normally the cam head 73 holds the block 65 away from the adjacent cam, so that the projection 70 of pin

66 is out of engagement with clutch disk 57. Therefore, as long as the rear end of lever 74 (or 74') remains in engagement with block 75, the cams are stationary and there is no movement of levers 41-44. When the operator depresses pedal 77, the rear end of lever 74 is raised out of engagement with block 65. As soon as one of the holes 71 in the continuously rotating clutch disk 57 comes in alignment with the locking head 70 of pin 66, the tensioned spring 68 asserts itself and pushes the head 70 into the aligned clutch hole, whereupon the cams rotate with disk 57. If the operator keeps his foot on pedal 77 and thus holds the cam head 73 in raised position, the cams continue to rotate with the shaft; but if the operator releases the pedal after depressing it, as he is supposed to do, the cam head 73 drops back into normal locking position. Consequently, after the cams have made one revolution, the cam face 72 of block 65 comes in contact with the cam head 73 and is forced to the left (as viewed in Fig. 7), whereby the locking projection 70 is withdrawn from the clutch disk 57 and the cams remain stationary. The same explanation applies when the pedal 78 is depressed to connect the cams 55-56 with the operating shaft 48.

Let us now see what happens during the interval in which the cams 53-54 are connected with the driving shaft for one revolution. While the roller 58 of lever 41 rides on the high track 53^a, the roller 59 of lever 42 rides on the low track 54^b. This means that while the valve lever 34 is held down in closing position, the lever 35 remains up in open position, so that a filler on support 6 is open to the vacuum pump for approximately a half revolution of the cams. This interval is sufficient to cause partial evacuation of the annular space between the glass cylinders of the bottle. When the high track 54^a passes under roller 59 of lever 42, the roller 58 encounters the low track 53^b, whereby the lever 35 is rocked down to closing position and the lever 34 is raised to connect the evacuated filler with the silver solution in receptacle 11. Instantly the vacuum in the bottle draws in the contents of the cup. As the cams complete one revolution, the block 65 encounters the cam head 73 of lever 74, and the cams are automatically disconnected from the driving shaft, as already explained.

The operation described in the preceding paragraph is also applicable to the cam mechanism shown in Fig. 6, which controls the evacuating and filling of the bottle on support 7, except that, while the first bottle is being filled, the bottle on support 7 is being evacuated. This gives the operator a chance to load one side of the machine while the other is being filled.

There remains to be described the connections for automatically tilting the acid cups

30 and 31 just before (or just as) the silver solution is drawn into the bottle. Since these connections are the same for both acid cups, a description of one will do for both. As 5 already explained, each acid cup is tiltably mounted on a tubular extension which allows the cup to connect with the acid storage bottle 28. Each cup is provided with a cylindrical bearing 81 (see Fig. 4), which has a 10 rearwardly extending arm 82 connected to the adjacent lever 41 by a link 83. The link 83 for cup 31 is connected to lever 44. Since the levers 41 and 44 are beneath the table, while the arms 82 are at the side of the table, 15 the links 83 are bent as shown in Fig. 4, in order to permit vertical movement of the parts. When the front ends of levers 41 and 44 are raised to rock the valve arms 34 and 37 upwardly into open position, the links 20 83 are thrown up at the same time to tilt the acid cups toward the receptacles 11 and 12. The required amount of acid is thus added to the silver solution just before (or perhaps just at) the moment when the contents 25 of the solution receptacles are drawn into the evacuated filler. The acid cannot be added to the silver solution for any length of time before the filling operation, as otherwise the silver would begin to precipitate.

20 The operation of the machine as a whole will be clear from the preceding description, but it may be well to summarize the sequence of events from the time a bottle is put on until removed. After the operator has 25 placed a bottle on the table in connection with the tubular support 6, he depresses pedal 77. Almost instantly the valve arm or pinch-cock 30 is thrown open to connect the bottle with the vacuum pump, while the arm 34 remains closed. After about half a revolution of 35 shaft 48, the vacuum valve 35 is closed and the valve 34 is raised. At the same time, the acid cup is tilted to add the proper amount of acid to the silver solution just as the latter 40 is being sucked into the evacuated bottle. The suction action is sufficiently powerful to empty the solution receptacle almost instantly, and the mixture of silver solution and acid enters the evacuated bottle with a rapid 45 swirling motion. The filled bottle is removed and a fresh one put in its place. The filled bottle is then subjected to a further treatment to cause a uniform precipitation of metallic silver on the walls of the vacuum chamber. It will not be necessary to say anything 50 about this further treatment because that forms no part of the present invention. The time elapsing between the loading of an empty bottle and the removal of a filled bottle 55 is not more than about eight or ten seconds. If desired, the machine may have only one bottle support, but I prefer to make provisions for handling two bottles at a time.

Although I have shown and described a 60 specific construction, I want it understood

that I do not intend to be limited to the details set forth. It is manifest that changes and modifications will suggest themselves to the skilled mechanic without departing from the scope of the invention as defined in the 70 following claims.

I claim as my invention:

1. In a filling machine of the class described, a fixed tubular member extending upwardly at an angle for receiving the tubular extension of a double-walled glass bottle in an airtight fit, a support cooperating with said member to hold the connected bottle in a stationary inclined position with the base projecting downward, means for connecting said tubular member with a vacuum pump, connections leading from said tubular member to a receptacle containing a suitable solution, valve mechanism for connecting said tubular member first with the vacuum pump 80 and then with said receptacle, and means for operating said valve mechanism.

2. In a filling machine of the class described, a fixed tubular member extending upwardly at an angle for receiving the tubular extension of a double-walled glass bottle in an airtight fit, a support cooperating with said member to hold the connected bottle in a stationary inclined position with the base projecting downward, means for connecting said tubular member with a vacuum pump, 90 means for connecting said tubular member with a receptacle containing a suitable solution, a valve for controlling each of said connections, and cam-controlled means for 100 operating said valves in properly timed relation to connect said tubular member alternately with the vacuum pump and with said receptacle.

3. In a filling machine of the class described, a fixed tubular member extending upwardly at an angle for receiving the tubular extension of a double-walled glass bottle in an airtight fit, a support cooperating with said member to hold the connected bottle in 110 a stationary inclined position with the base projecting downward, a pair of flexible tubes connected with said member, means for connecting one of said tubes with a vacuum pump, means for connecting the other tube 115 with a receptacle containing a suitable solution, a pivoted arm for pinching each tube, and cam-controlled connections for operating said arms in properly timed relation to connect said member alternately with the 120 vacuum pump and with said receptacle.

4. In a filling machine of the class described, a tubular member for receiving the tubular extension of a double-walled glass bottle, means for holding the connected bottle in an inclined position with the base projecting downward, means for connecting said member with a vacuum pump, means for connecting said member with a receptacle containing a suitable solution, a valve for 130

controlling each of said connections, a rotary shaft, a pair of cams mounted on said shaft and normally disconnected therefrom, a pair of levers controlled by said cams for operating said valves to connect said tubular member first with the vacuum pump and then with the solution receptacle, and clutch means for connecting said cams to said shaft for a predetermined interval to actuate said levers.

10. 5. In a filling machine of the class described, a tubular member for receiving the tubular extension of a double-walled glass bottle, means for holding the connected bottle in an inclined position with the base projecting downward, means for connecting said member with a vacuum pump, means for connecting said member with a receptacle containing a suitable solution, a valve for controlling each of said connections, a rotary shaft, a pair of cams mounted on said shaft and normally disconnected therefrom, a pair of levers controlled by said cams for operating said valves, to connect said tubular member first with the vacuum pump and then with the solution receptacle, and pedal-operated clutch mechanism for connecting said cams to said shaft for one revolution and automatically disconnecting the cams from the shaft at the end of one revolution.

20. 6. In a filling machine of the class described means for connecting a double-walled glass bottle with a vacuum pump, an open receptacle connected with a source of silver solution, a tube for connecting the evacuated bottle with the silver solution in said receptacle, said tube having an end dipping into the solution in said receptacle, and automatic means for adding an amount of acid to the silver solution in said open receptacle just before or as the solution is drawn into the evacuated bottle.

7. In a filling machine of the class described, means for connecting a double-walled glass bottle with a vacuum pump, means for connecting the evacuated bottle with a receptacle containing a silver solution, a tiltable cup mounted adjacent said receptacle, and properly timed connections for automatically tilting said cup to pour the acid content into the silver solution in the receptacle just before or as the solution is drawn into the evacuated bottle.

8. In a filling machine of the class described, a fixed tubular member extending upwardly at an angle for receiving the tubular extension of a double-walled glass bottle in an airtight fit, a support cooperating with said member to hold the connected bottle in a stationary inclined position with the base projecting downward, means for connecting said tubular member with a vacuum pump, connections leading from said tubular member to a receptacle containing a suitable solution, valve mechanism for connecting said tubular member first with the vacuum pump

and then with said receptacle, means for operating said valve mechanism, and means for automatically adding a measured amount of acid to the silver solution in the receptacle just before or as the evacuated bottle draws in the solution.

9. In a filling machine of the class described, a tubular member for receiving the tubular extension of a double-walled glass bottle, means for connecting said member with a vacuum pump, means for connecting said member with a receptacle containing a silver solution, valve mechanism for connecting said tubular member first with the vacuum pump and then with the solution receptacle, means for operating said valve mechanism, an acid cup tiltably mounted adjacent said receptacle, and connections for automatically tilting said cup to add an amount of acid to the silver solution in the receptacle just before or as the evacuated bottle draws in the solution.

10. In a filling machine of the class described, a tubular member for receiving the tubular extension of a double-walled glass bottle, means for connecting said member with a vacuum pump, means for connecting said member with a receptacle containing a silver solution, a valve for controlling each of said connections, a rotary shaft, a pair of cams mounted on said shaft and normally disconnected therefrom, a pair of levers controlled by said cams for operating said valves to connect said tubular member first with the vacuum pump and then with the solution receptacle, clutch means for connecting said cams to said shaft for a predetermined interval to actuate said levers, an acid cup tiltably mounted adjacent said receptacle, and means controlled by one of said cams for tilting said cup to add an amount of acid to the silver solution in the receptacle just before or as the evacuated bottle draws in the solution.

11. In a filling machine of the class described, a tubular member for receiving the tubular extension of a double-walled glass bottle, means for connecting said member with a vacuum pump, means for connecting said member with a receptacle containing a silver solution, a valve for each of said connecting means, a continuously rotating shaft, cam mechanism mounted on said shaft but normally disconnected therefrom, pedal-operated means for coupling said cam mechanism to said shaft for one revolution thereof, connections between said cam mechanism and said valves for so operating the latter that said tubular member is first connected with the vacuum pump and then with the receptacle containing the silver solution, an acid container associated with said receptacle, and means controlled by said cam mechanism for causing said container to discharge a quantity of acid into the silver solution

- just before or as the receptacle is connected with the evacuated bottle.
12. Bottle-filling apparatus comprising a table, a pair of tubular members mounted on the table for receiving the tubular extensions of double-walled glass bottles, connections between said members and a vacuum pump, valves for controlling said connections so that only one bottle at a time is open to the pump, a pair of receptacles supported by the table and communicating with a supply of silver solution, an outlet tube leading from each receptacle to one of said tubular members, two sets of valves for controlling said outlet tubes that when one tube is open the other is closed, cam-controlled mechanism for operating each set of valves to connect the associated member first with the vacuum pump and then with the receptacle containing the silver solution, an acid holder associated with each solution receptacle, and means operated by said mechanism to cause each acid holder to discharge a quantity of acid into the adjacent receptacle just before or as the solution in that receptacle is drawn into the evacuated bottle.
13. In a machine of the class described, a rigid tubular member extending upwardly and rearwardly, the upper open end of said member having a flexible tubular portion for receiving the tubular extension of a double-walled vacuum bottle in an airtight fit, and vacuum means for drawing a solution into the space between the walls of said bottle through said tubular member.
14. In a machine of the class described, an open tubular member mounted rigidly on a support so as to extend upwardly and rearwardly for receiving the tubular extension of a double-walled vacuum bottle in an airtight fit, a tube leading from said member to connect the same with a source of vacuum, a second tube leading from said member to connect the same with a solution receptacle, valve mechanism for controlling said tubes, and connections for operating said valve mechanism to connect said tubular member first with the source of vacuum and then with the solution receptacle.
15. In a machine of the class described, a pair of flexible tubes mounted horizontally in substantially axial alignment, a rigid T-shaped tubular member connecting said tubes, said member extending upwardly and rearwardly for receiving the tubular extension of a double-walled vacuum bottle in an airtight fit, a pair of pivoted levers supported transversely of said flexible tubes, so that the downward movement of each lever compresses the associated tube to close the same, means for connecting one of said tubes with a source of vacuum, means for connecting the other tube with a solution receptacle, and connections for alternately operating said levers to connect a bottle on said tubular member
- first with the vacuum and then with the solution receptacle.
16. In a machine of the class described, the combination of a table, a tubular member mounted on said table so as to extend upward at an incline, the upper open end of said member being adapted to receive the tubular extension of a double-walled vacuum bottle in an airtight fit, and vacuum means for drawing a solution into the space between the walls of said bottle through said tubular member.
- MINER P. WETMORE.
